UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL ATTACHING.

1,409,359.

Specification of Letters Patent. Patented Mar. 14, 1922.

Application filed May 22, 1920. Serial No. 383,436.

To all whom it may concern:

Be it known that I, FREDERIC E. BERTRAND, a citizen of the United States, residing at Lynn, in the county of Essex and

5 State of Massachusetts, have invented certain Improvements in Heel Attaching, of which the following description, in connection with the accompanying drawings, is a specification, like reference characters on the 10 drawings indicating like parts in the several figures.

This invention relates to the manufacture of shoes and more particularly to the clamping of heels to shoes and to the applying of 15 coverings to the breasts of heels.

In attaching wood heels to shoes it is usual, after the heel seat of the shoe has been fitted to the heel to be attached, to apply a coating of suitable adhesive to the 20 heel seat of the shoe or to that of the heel or to both and, after correctly positioning the heel with respect to the shoe, to clamp the heel to the shoe, the pressure being applied directly to the heel and to the shoe 25 through the last on which it is mounted. After the adhesive has set so that the shoe may be further operated upon, the heel breast covering ordinarily consisting of a split portion of the sole, is brought into position, with a film of adhesive between it and 30 the heel breast, and is bound to the heel by means of a band of suitable material, such as a piece of tape. The conformation of the clamps ordinarily used to clamp wood heels 35 to shoes is such as to interfere with the convenient binding in place of the breast covering while its adhesive sets. Hence the practice has been to make two distinct operations of the heel attaching and the applying of 40 breast covering.

It is an object of the present invention so to clamp the breast covering to the breast of a wood heel as to permit the performance of this operation immediately after the 45 clamping of the heel to the heel seat of a shoe. Thus the films of adhesive between the heel and the shoe and between the heel breast covering and the breast of the heel will set simultaneously with a resulting saving in 50 time as compared to the usual practice prior to this invention.

A further object of the invention is the provision of an improved heel attaching clamp so constructed and arranged as to be 55 applicable to heels of varying form and size

to apply pressure to the heel without damage thereto, to clamp the heel firmly to the heel seat of a shoe. Considered from this aspect, features of the invention include improved means, exemplified as a heel cup, having 60 rubber rolls, arranged to apply pressure to the contour surface of a heel without damage to the covering thereof, and an improved tread plate, illustrated as pivotally and adjustably carried by the heel cup, to apply 65 pressure to the toplift of the heel.

Another feature of the invention consists of an improved heel breast covering clamp comprising a pressure applying element of 70 yieldable or flexible material, such as a sheet of rubber, together with means for supporting said element approximately to conform to the curve of a heel breast whereby said element may be utilized, when pressure is suitably applied thereto, to clamp the 75 breast covering to the breasts of heels. While this breast clamp may advantageously be used in combination with a suitable heel clamp, and the present invention contemplates such use, it should be distinctly understood that the breast clamp is capable of use 80 separately from a heel clamp, if desired or expedient, and that such is also within the contemplation of the invention.

A further feature of the invention consists of improved means for bringing a heel breast engaging member into contact with a heel breast and for applying clamping pressure thereto.

In another aspect the invention contemplates the utilization of sufficient pressure while clamping a heel to the heel seat of a shoe to cause the heel to mold the heel seat of the shoe whereby a close fit of the heel to the upper of the shoe is insured. By suitably 90 distributing the clamping pressure over the different parts of a wood heel, while the shoe to which the heel is being attached is supported on its last, such a molding pressure may be applied without damage to the 100 heel and is advantageous both as regards the appearance of the shoe and the firmness of the attachment of the heel to the shoe.

With the above and other objects and features in view, the invention will now be described with reference to the illustrative machines of the accompanying drawings and pointed out in the claims.

In the drawings,

Fig. 1 is a perspective view showing a 110

portion of a bench to which are attached clamps embodying certain features of this invention;

Fig. 2 is an elevation showing in detail the 5 heel cup of Fig. 1 and associated parts in clamping relation to a shoe and the heel thereof;

Fig. 3 is a rear view of the heel cup of 10 Fig. 2, looking in the direction of the arrow of that figure;

Fig. 4 is a perspective view of the tread 15 plate of Fig. 2;

Fig. 5 is a side elevation of a modified 20 form in which a heel breast clamp is carried by the heel cup;

Fig. 6 is a similar view with parts broken 25 away in which the pressure applying member of the breast clamp is shown in the position it occupies after it has been moved to heel breast engaging position, but before 30 clamping pressure has been applied thereto;

Fig. 7 is a perspective view with parts 35 broken away of the heel cup of Fig. 5 showing it in operative relation to the heel of a shoe but before the breast engaging member 40 has been brought into operative position; and

Fig. 8 is a perspective view, with parts 45 broken away, of the pressure applying member of the heel breast clamp showing it in clamping relation to the breast of a heel.

As shown in Fig. 1, a series of heel clamps 50 of the present invention may be supported upon a bench 12 of any suitable form.

Preferably, a sufficient number of the clamps 55 is utilized such that the operative may work from one end to the other of the series, clamping a heel to a shoe by each clamp until, by the time he reaches the end of the 60 series, the film of adhesive between the heel and the shoe in the first clamp will have set to such an extent that the shoe can be removed safely from the clamp which may then be utilized to clamp a heel to another shoe.

Thus, after his first progression along the 65 line of clamps the operative, upon clamping a heel to a shoe with each clamp, finds the shoe on the next clamp in such condition that it may be removed and that clamp again 70 utilized.

In practice the number of clamps necessary that the series may be so utilized 75 will vary somewhat with the skill and speed of the operative and with the character of adhesive used. As a practical proposition it 80 has been found that with the clamps of the form shown in Fig. 1, from twenty-four to forty-eight are desirable.

Each clamp, as shown, is provided with a 85 jack consisting of a standard or sleeve 14 fastened to the bench in any suitable manner and carrying, for limited sliding movement, a plunger 16 having at its upper end a last pin or spindle 18, the latter being preferably bent forward somewhat for a reason 90 which will be hereinafter explained. Plun-

ger 16 is normally held in its upper position by a spring 20 housed within sleeve 14, movement of the plunger under the influence of the spring being limited as by a screw 22 threaded in the sleeve and entering an elongated cavity 24 in the plunger 16. Fulcrumed to each standard 14 near its base is a hand lever 26 to which is attached, at a short distance from its fulcrum, a pair of rods 28 each of which is formed intermediate its length with a coil 30 and is pivoted at its upper end to one of a pair of hooks 32 carried by a heel cup 34.

Referring now more particularly to Figures 1 to 4, this heel cup, as shown, is provided at its rear with a pair of pins 36 suitably supported thereby and each carrying a roll 38 of rubber or other soft and yieldable material. These two rolls are arranged with their axes converging, in the illustrated form 85 approximately at right angles to one another, and are so positioned that they may engage the rear portion of the contour surface of a heel on opposite sides of the median plane thereof.

The heel cup 34 is illustrated as provided with a pair of upwardly extending arms 40 each provided with a series of holes, the holes in the two arms being in alinement to receive a pin 42 which acts as a pivotal support for a tread plate 44, the latter being provided with a series of holes 46 through any one of which pin 42 may be passed. It is apparent that means is thus provided for adjusting the tread plate relatively to the heel 100 cup both in the direction of the height of a heel and in the direction of the longitudinal axis of the shoe to which the heel is to be attached. Also, since the tread plate is carried by pin 42 it is capable of adjustment 105 to any position which may be necessary on account of variations in the size and shape of different heels to be attached. Moreover, since the heel cup is pivotally connected to rods 28, it may swing with respect thereto 110 to conform to the pitch of different heels.

The tread plate 44 is preferably made of a length less than the length of the toplifts of the heels to be attached and is provided at the rear with a lip 48 arranged to engage the 115 contour surface of the toplift and insure that the tread plate shall not extend over the forward portion thereof.

At such time as any of the heel cups are not in clamping relation to the heel of a shoe, 120 rods 28 may conveniently be swung rearwardly and coils 30 may be hooked over a suitable portion of the bench, such as the flange 50 of Fig. 1, this forming a convenient mode of holding the heel cups and rods 125 28 in such position that they will be out of the way of the operative and at the same time in an easily accessible position.

To assist in holding the heel cups in a position convenient to the operative at such 130

times as they are not in use, they may be provided with lugs 52 somewhat to the rear of the hooks 32 and arranged to engage rods 28 and limit the swinging movement of the 5 heel cups. Since the center of gravity of each heel cup is to the rear of its hooks 32, the heel cups naturally come to rest in the position shown in Fig. 1.

In operation, a last on which is mounted 10 a shoe to which a heel is to be attached is placed upon the pin 18. Before the adhesive is applied the heel seat of the shoe is trimmed to fit the concavity of the heel which is to be attached and after the coating of adhesive 15 has been applied to the heel seat of the shoe and of the heel, the heel is positioned in proper relation to the heel seat of the shoe and the heel cup swung forward so that its rolls 38 engage with the contour surface of the 20 heel. The tread plate having been properly adjusted, it is brought into engagement with the toplift of the heel, its lip 48 contacting with the contour surface of the toplift to position it with respect thereto. Next 25 the lever 26 is swung downward tensioning the rods 28 so that the heel cup applies a clamping pressure to the heel. The position to which the lever 26 is swung is such that the lever 26 and the rods 28 act as a 30 toggle couple to hold the heel cup in clamping position as shown in Fig. 5. It may be here noted that the inclination of the last pin 18 is such that the pressure applied to the heel by the heel cup has a small component in a direction towards the forepart of the shoe, this being of material assistance in properly positioning the heel upon the heel seat of the shoe and insuring that the edge of the heel properly contacts with the 35 shoulders formed in the sole of the shoe at the front of the heel seat.

The pressure with which the heel is thus clamped to the shoe may advantageously be great enough to cause the heel to mold the 40 heel seat of the shoe, thus compensating for such irregularities as may exist in the heel seat due to the roughness of the heel seat fitting operation and insuring a close fit between the upper edge of the heel and the 45 upper of the shoe. With the clamping pressure well distributed over the different parts of the heel such a molding pressure may be applied without damage to the heel, the yielding nature of the rolls 38 being such as 50 to enable them to distribute that portion of the pressure which they apply over a substantial area, and their form and mounting permitting them to move over the covered surface of the heel as they are brought into 55 position without damage thereto.

Referring now to Figs. 5 to 8, the heel cup thereof, while generally similar to Figs. 1 to 4, is provided with a single upstanding arm 60 provided with a dove-tailed slot in which 65 is mounted for sliding movement a carrier 62

(see Fig. 7) by which is pivotally supported a tread plate 64 provided at its rear with a lip 66. The carrier 62 may be retained in any one of several positions by means of a pin or other suitable retaining member 68 70 passing through the arm 60 and into one of a series of holes 70 formed in the carrier 62. Fulcrumed to the arm 60, as at 72, is a lever 74 provided with a coil spring 75 the tension of which tends to throw it upwardly into the 75 position of Fig. 7. Lever 74 consists, as shown in Fig. 7, of two parallel arms, one of which is provided with a projection arranged to engage a pin 77 carried by arm 60 to limit the upward movement of the lever. 80 This lever may conveniently be provided with a handle portion 76. Fulcrumed to lever 74 at 78 is a second lever 80 to the lower end of which is connected a pressure transmitting member consisting of a rod 82 85 (see Fig. 6) on which is pivotally mounted a pair of arms 84 each of which supports a U-shaped rod 86. These two rods 86 form a pair of supports over which is loosely stretched a pressure applying member consisting of a piece of rubber tubing 88. Since the rods 86 conform approximately to the curvature of the breast of a Louis heel it will be seen that they support the rubber 88 in such position that with slight pressure it 90 will conform to the curvature of the breast of the heel over its entire height. A stop illustrated as a screw 91 is carried by lever 74 in such position as to limit the downward and forward movement of lever 80. 95

A latch may conveniently be carried by the heel cup so arranged as to be capable of retaining lever 74 in either the inoperative position of Fig. 7 or in the pressure applying position of Fig. 5. In the illustrated embodiment of the invention ~~the~~ comprises a lever 90 fulcrumed on a pin 92 carried by the heel cup and provided with a spring 94 tending to hold it in the position shown in Fig. 7. Lever 90 is provided with an adjustable 100 detent 96 illustrated as a screw and arranged to engage the surface 98 of lever 74 to hold the latter in the position of Fig. 7 or to engage the surface 100 thereof to hold the lever in the position of Fig. 5. This latch 110 may be released merely by swinging the lever a short distance in a clockwise direction as viewed in Fig. 7.

In using this breast clamp, the latter is retained in inoperative position as indicated 120 in Fig. 7 during the clamping of the heel to the shoe. After this operation is completed, the operative applies the adhesive which is to hold the heel covering to the breast of the heel, and manually presses 125 the breast covering into place. Next the end of the breast covering is tucked under the toplift of the heel this being readily done by reason of the fact that the tread plate does not extend over the forward por- 130

tion of the toplift. The front edge of the toplift may be easily lifted a little with any suitable flat instrument such as a screw driver and the edge of the breast covering tucked in. Then, releasing the latch, the operative swings the lever 74 downward into the position of Fig. 6, the construction being such that the rubber 88 moves into position without dragging over the breast covering or in any way interfering therewith. At this time it may be noted that the rubber 88 of the breast clamp is in breast engaging position but no substantial amount of pressure is being applied. Next the operative 15 swings lever 80 forward. This applies a yielding pressure sufficient to clamp the breast covering in place. It may be noted at this time that the reactive forces caused by the pressure of the rubber against the breast of the heel and acting upon arms 84 carried by the lever 80 are such as to tend to swing the lever 80 in the direction of the 20 stop 91 so that no latch is required to hold the different parts in pressure applying 25 position.

In releasing the breast clamp, lever 80 should first be swung to the position of Fig. 6. Then, if a slight pressure is applied to lever 74, the latch may easily be released, 30 whereupon lever 74 will swing to inoperative position under the influence of spring 75 and will be there retained by the latch. After this the heel cup may be released by bearing upward on lever 26 and swung to a position 35 corresponding to that of Fig. 1, after which the last and shoe may be removed from the jack.

Having described my invention, what I claim as new and desire to secure by Letters 40 Patent of the United States is:

1. A heel cup constructed and formed to be used to clamp a heel to a shoe and having a heel engaging roll.

2. A heel cup constructed and formed to 45 be used to clamp a heel to a shoe and having a roll arranged to engage the rear portion of the contour surface of a heel.

3. A heel clamp having a heel cup constructed and formed to be used to clamp a 50 heel to a shoe and provided with roller means arranged to engage the rear portion of a heel on both sides of its median plane for applying pressure thereto.

4. A heel cup constructed and formed to 55 be used to clamp a heel to a shoe and having a heel engaging roll formed of yielding material.

5. In a device of the class described, in combination, a work support, a clamping 60 head, spaced and linked toggle members mounted on opposite sides of the support and carrying the head, a handle to move the knuckles of the toggle members to move the head to and from clamping position, and 65 a bench to carry the work support and

toggle members and having a projecting portion to engage the toggle members in their inoperative position.

6. In a heel clamp, a heel cup constructed and arranged to clamp a heel to a shoe and 70 provided with a rubber heel engaging surface.

7. In a device of the class described, in combination, a support, a clamping head movable toward and from the support and 75 formed with relatively adjustable work-engaging members, and means comprising spaced guiding members on opposite sides of the support to move the head to effect a clamping action co-operatively with the sup- 80 port.

8. A heel cup constructed and arranged to clamp a heel to a shoe and provided with a pair of rolls arranged respectively to engage the rear portion of a heel on opposite 85 sides of its median plane for applying pressure thereto.

9. A heel cup constructed and arranged to clamp a heel to a shoe and provided with roller means having converging heel engag- 90 ing surfaces for applying pressure to the contour surfaces of heels.

10. A clamp to press a heel against the heel seat of a shoe and having a rubber surface arranged to contact with the contour 95 surface of a heel over spaced areas on opposite sides of its median plane.

11. A heel clamp having a heel cup constructed and arranged to clamp a heel to a shoe and provided with roller means having 100 heel engaging surfaces converging towards the rear of the heel to be clamped.

12. A heel clamp comprising a support, a heel cup provided with a roll arranged to engage the rear portion of a heel to be 105 clamped to the heel seat of a shoe carried by said support, and means operable to cause relative movement of said support and said heel cup to clamp the heel to the heel seat of the shoe.

13. A heel clamp comprising a support, a heel cup provided with roller means arranged to engage the rear portion of a heel on both sides of its median plane, and means operable to cause relative movement of said support and said heel cup to clamp the heel to the heel seat of a shoe carried by said support.

14. A heel clamp comprising a support, a heel cup provided with roller means having 120 curved surfaces with their respective heel engaging portions converging towards the rear, and means operable to cause relative movement of said support and said heel cup to clamp a heel to the heel seat of a shoe 125 carried by said support.

15. A heel clamp comprising a jack for supporting a last with a shoe mounted thereon, a heel cup provided with a roll having a surface of yielding material arranged to 130

- engage the rear portion of a heel to be clamped to the heel seat of the shoe, and means operable to cause relative movement of the jack and the heel cup to clamp the heel to the heel seat of the shoe.
16. A heel clamp comprising a jack for supporting a last with a shoe mounted thereon, a heel cup provided with a rubber roll arranged to engage the rear portion of a heel to be clamped to the heel seat of the shoe, and means operable to cause relative movement of the jack and the heel cup to clamp the heel to the heel seat of the shoe.
17. A heel clamp comprising a jack for supporting a last with a shoe mounted thereon, a heel cup provided with a pair of rolls angularly arranged to engage the rear portion of the heel on both sides of its median plane, and means operable to cause relative movement of the jack and the heel cup to clamp the heel to the heel seat of the shoe.
18. A device to clamp a heel to a shoe comprising, in combination, a support for a shoe, spaced links mounted on opposite sides of said support, a head mounted on said links and carried thereby from an inactive position to active position above a heel placed on the heel seat of a shoe on the support, means to engage the tread surface of the heel, and means to engage another surface of the heel, both of said means being carried by the head and one of said means being constructed and arranged to be bodily adjusted relatively to the other said means to engage heels of different sizes.
19. A heel clamp comprising a jack for supporting a last with a shoe mounted thereon, a heel cup provided with roller means of yielding material arranged to engage the rear portion of a heel on both sides of its median plane, and means operable to move the heel cup relatively to the jack to clamp the heel to the heel seat of a shoe mounted on a last carried by the jack.
20. A heel clamp comprising a jack, a heel cup arranged to engage the heel of a shoe mounted on a last carried by said jack, and means relatively to move said jack and said heel cup to clamp the heel to the shoe, all so arranged that said movement has a component in a direction tending to move the heel forwardly on the shoe.
21. A heel press comprising a bench, a jack supported by said bench, a heel cup in operative relation to said jack, a rod connected to said heel cup and provided with means arranged to co-operate with a portion of said bench to limit movement of said rod while said heel cup is in inoperative position, and means arranged to cause longitudinal movement of said rod to force said heel cup into clamping relation to the heel of a shoe supported by said jack.
22. A press comprising a bench, a support on said bench, a clamping member in operative relation to said support, a rod connected to said member and provided with a coil arranged to co-operate with a portion of said bench to limit movement of said rod while said member is in inoperative position, and means arranged to cause longitudinal movement of said rod to force said member into clamping relation to the support.
23. In a clamping device for shoe heels, the combination with a last support, of a clamp carrier pivotally mounted with reference to the last support to swing about the same and including spaced guiding elements, and a clamp carried by said elements comprising relatively adjustable surfaces for clamping the bottom and side of the heel.
24. A heel press comprising a bench, a jack supported by said bench, a heel cup in operative relation to said jack, a rod connected at one end to said heel cup and provided with a coil arranged to co-operate with a portion of said bench to limit movement of said rod while said heel cup is in inoperative position, and a lever pivoted to the other end of said rod and operable to cause longitudinal movement of said rod to force said heel cup into clamping relation to the heel of a shoe supported by said jack.
25. A heel cup provided with a separate tread plate pivotally mounted thereon and having a lip at its rear.
26. A heel cup provided with a separate tread plate pivotally mounted thereon and shorter than the toplift of the heels to which it is to be applied and having a lip at its rear.
27. A heel cup provided with a separate tread plate pivotally mounted thereon and having means arranged to engage the rear part of the contour surface of the toplift of a heel to position the tread plate with respect to the heel.
28. A heel engaging device comprising, in combination, a carrier member and a tread-engaging member, each of said members having a series of holes therethrough, the two series being at right angles in the assembled device, and a pin to be placed in registered holes to provide a pivotal mounting at a desired height and lateral position for the tread-engaging member.
29. A heel cup provided with an upstanding arm and a tread plate pivotally mounted thereon and adjustable relatively thereto.
30. A heel clamp provided with a shoe support and a heel cup bodily movable relatively to the support and arranged to engage the rear portion of the contour surface of a heel, said heel cup carrying a tread plate adjustable toward and from the body portion of the heel cup to accommodate heels of different heights.
31. A heel clamp provided with a shoe support and a heel cup bodily movable relatively to the support and arranged to

engage the rear portion of the contour surface of a heel, said heel cup carrying a pivotally supported tread plate adjustable toward and from the contour surface engaging portion of the heel cup to accommodate heels of different heights and shapes.

32. A heel cup provided with a pair of upstanding arms, each arm provided with a series of holes, the holes in one arm alining 10 with those in the other arm, a tread plate provided with a series of holes, and a pin arranged to pass through any one of the holes in the tread plate and any pair of holes in the arms, to support the tread plate 15 in variable relation to the arms.

33. A heel clamp having a heel cup, a rod pivoted to the heel cup and by movement of which the heel cup may be moved 20 into clamping relation to a heel, and a stop carried by the heel cup to limit the relative movement of the heel cup and the rod.

34. A heel clamp comprising a support, means to clamp a heel to a shoe carried by 25 said support, and separate means to clamp a breast covering to said heel.

35. A heel clamp comprising a support for a shoe, a heel cup, means to cause relative movement of said support and said heel cup to clamp a heel to a shoe carried by said 30 support, and independently operable means to clamp a breast covering to said heel.

36. A heel clamp having a heel cup and independently operable means carried by 35 said heel cup for clamping a breast covering to the breast of a heel.

37. A heel clamp comprising, in combination, a shoe support, means to press a heel against the heel-seat of a shoe supported thereby, and means to clamp a breast covering 40 to the breast of the heel so pressed against the shoe.

38. A heel clamp having a heel cup provided with a roll arranged to engage the rear portion of the contour surface of a heel 45 and a breast clamp carried by said heel cup for clamping a breast covering to the breast of a heel.

39. A heel clamp comprising, in combination, a shoe support, a member movable toward a heel on a shoe supported thereby, 50 means on said member to engage the rear surface of the heel, and means carried by said member to clamp a breast covering to the breast of the heel.

40. A heel breast covering clamp having 55 a pressure applying member comprising a pair of rods shaped to conform approximately to the curvature of a heel breast, and a sheet of yieldable material supported by 60 said rods.

41. A heel breast covering clamp provided with a sheet of rubber arranged to conform to the breast of a heel, rigid means to hold said sheet extended approximately 65 to conform to the breast of a heel, and means

to cause said sheet of rubber to apply a clamping pressure to the breast of the heel.

42. A heel breast covering clamp having a pressure applying member comprising a pair of U shaped rods and a sheet of rubber 70 supported by said rods.

43. A heel breast covering clamp comprising a movable support, a pair of U shaped rods carried thereby, and a piece of rubber tubing carried by said rods. 75

44. A heel clamp having a heel cup, a heel breast clamp carried thereby, said heel breast clamp comprising a heel breast engaging member, a lever fulcrumed to said heel cup for moving said breast engaging member into heel breast engaging position, and a second lever fulcrumed to said first named lever and carrying said heel breast engaging member for causing said heel breast engaging member to apply pressure 80 to the breast of a heel.

45. A heel clamp comprising a support for a shoe, a heel clamp and a heel breast clamp carried by said heel clamp and having a breast covering engaging element and means 90 to cause said element to apply pressure to the breast covering of the heel of a shoe in a direction having components in directions towards the sole of the shoe and towards the breast of the heel, in combination with means 95 independently to operate the two said clamps.

46. A heel clamp having a support for a shoe, a heel cup, means to cause said heel cup to clamp a heel to a shoe carried by said 100 support, a lever carried by said heel cup, a latch to hold said lever in either operative or inoperative position, and a breast covering clamp carried by said lever and operable to clamp a covering to the breast of the shoe 105 on said support.

47. A heel clamp having a heel pressing member, a lever fulcrumed thereto, and a pressure applying member operated by said lever for clamping a breast covering to the 110 breast of a heel.

48. A heel clamp having a heel cup, a compound lever fulcrumed thereto, a pressure applying member carried by said compound lever for clamping a breast covering to the 115 breast of a heel, and a latch to hold said lever in clamping position.

49. A clamp member provided with a pressure transmitting member, a pair of arms pivotally carried thereby, a rod carried by each arm, and a sheet of rubber carried by said rods and arranged to apply a clamping pressure to the breast of a heel. 120

50. That improvement in attaching wood heels to shoes which includes positioning a 125 wood heel in the desired relation to the heel seat of a shoe with a film of adhesive between the heel and the heel seat of the shoe and clamping the heel to the shoe with a pressure which causes the heel to mold the 130

heel seat of the shoe, and thereafter clamping a breast-covering against the breast of the heel with a film of adhesive between the heel breast and the covering, and allowing 5 the two films of adhesive to dry simultaneously under pressure.

51. That improvement in attaching heels to shoes which includes fitting the heel seat of a shoe approximately to the heel seat of 10 a heel to be attached, positioning the heel in the desired relation to the heel seat of the shoe with adhesive between the heel and the heel-seat, clamping the heel to the shoe, clamping a heel-breast covering to the breast 15 of the heel with adhesive between the heel breast and the covering, and allowing the adhesive between the heel and heel seat and

between the covering and the heel breast to dry while the heel and the covering are both so clamped. 20

52. That improvement in attaching heels to shoes which includes positioning a heel in the desired relation to the heel seat of a shoe with a film of adhesive between the heel and the heel seat of the shoe, applying pressure to clamp the heel to the heel seat of the shoe, and thereafter while said pressure is maintained clamping a breast covering to the breast of the heel with a film of adhesive therebetween. 25 30

In testimony whereof I have signed my name to this specification.

FREDERIC E. BERTRAND.
